CLAIM

The ornamental design for a toss game target, as shown and described.

DESCRIPTION

FIG. 1 is a perspective view of a toss game target showing my new design, the broken line showing of the cabinet being for illustrative purposes only;

FIG. 2 is a front elevational view thereof;

FIG. 3 is a back elevational view thereof;

FIG. 4 is a top plan view thereof;

FIG. 5 is a side elevational view of the left side of the toss game, the right side being a mirror image thereof; and

FIG. 6 is a bottom plan view thereof.
